UNITED STATES PATENT OFFICE.

EDWARD E. JONES, OF MALVERN, ILLINOIS.

SNAPPING-ROLLS FOR SHREDDERS.

SPECIFICATION forming part of Letters Patent No. 703,592, dated July 1, 1902.

Application filed April 8, 1901. Serial No. 54,863. (No model.)

To all whom it may concern:

Be it known that I, EDWARD E. JONES, a citizen of the United States, residing at Malvern, in the county of Whiteside and State of Illinois, have invented certain new and useful Improvements in Snapping-Rolls for Shredders; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention pertains to snapping-rolls for shredders and seeks to obviate certain objectionable features which now exist in devices of that class. Such rolls are now constructed in various ways, some of them being formed with smooth faces, some being provided with points to catch the stalks and assist them in their progress through the rolls, and still others being furnished with longitudinal corrugations. In all of these devices 20 the operation is not satisfactory, for the reason that frequently when an ear of corn is broken from a stalk by action of the rolls a part of the husk is drawn between such rolls, which continue to revolve without detaching 25 such husk from the ear. This results in the ear being held pendent against the face of the snapping-rolls instead of dropping upon the picker-rolls, as it should. The ear thus interferes with the feeding of the material 30 into the rolls, and in most cases the operator seeks to remove the ear with his hand. In this way many hands and arms have been drawn into the rolls, resulting in the loss 35 thereof to the operator and in some instances 40 in the loss of the operator's life. The same difficulty frequently arose by reason of the butt-end of a stalk refusing to pass through the rolls, whereby they became clogged and their capacity greatly reduced. I seek in my 45 invention to provide a device wherein any such interference with the feeding of material to the rolls is an impossibility.

In the drawings, Figure 1 is a front elevation of my invention. Fig. 2 is a similar 50 view with the position of the rolls slightly changed. Fig. 3 is a vertical cross-section in the line xx of Fig. 1.

The numerals 1 and 2 represent a pair of snapping-rolls placed one above the other and secured, respectively, on the shafts 3 and 4, which shafts are journaled in the usual manner in the frame of the machine.

55 The roll 1 is provided at each end with a circular head 5, adapted to engage similar heads 6 on the ends of the roll 2, whereby 60 such rolls are prevented from coming in contact with one another.

65 Seated on the shaft 3 is the gear-wheel 7, which engages a similar gear-wheel 8 on the shaft 4, whereby motion is imparted to such 70 shaft 4 and the roll 2. Power may be applied to the shaft 3 by any known method.

75 The rolls 1 and 2 have longitudinal corrugations or grooves 9, the corrugations of one roll meshing with those of the other, as shown in Fig. 3. Each roll is also provided with a spiral groove 10, running from end to end thereof and intersecting the longitudinal grooves 9 a number of times. This results in the formation of numerous teeth or elevations 11, such teeth being in rows lengthwise of the rolls and being also arranged spirally thereon in the form of spiral ribs located intermediate the several convolutions of the spiral grooves 10. It will be seen that the 80 spirals run in the same direction on each roll; but as these rolls revolve in different directions, as indicated by the arrows, the spiral groove in the roll 1, as well as the spiral row 85 of teeth 11 thereon, have a constant apparent movement toward the left when the rolls are in motion. The spiral groove and spiral row of teeth on the roll 2, on the contrary, have a constant movement (apparently) to the right when such rolls are in motion.

90 At certain points in the revolution of the rolls the teeth 11 of one roll will mesh with those of the other, as shown in Figs. 1 and 3. As the next succeeding longitudinal rows of teeth approach each other, however, they do 95 not mesh, but overlap each other slightly, as shown in Fig. 2. The contact will be still less with the next succeeding longitudinal rows of teeth, and in the operation of the machine the teeth of one roll cross and recross 100 those of the other roll continuously.

It will be evident that if a cornstalk had passed through one of the open spaces between the rolls, as shown in Fig. 1, and was

held therein by the butt-end thereof, a partial revolution of the rolls would cause such butt-end to be crushed to pieces and carried through the same. In the same way if an 5 ear of corn were caught and held by its husk or a part thereof the constant crushing and cross action of the teeth would immediately effect its release.

What I claim as my invention, and desire 10 to secure by Letters Patent of the United States, is—

1. A pair of snapping-rolls, having longitudinal corrugations, the corrugations of one roll being adapted to mesh with those of the 15 other roll; said rolls being further provided with spiral grooves, which, in operation, appear to travel from end to end of such rolls; the arrangement of such spirals being such that the groove on one roll moves in a direction 20 opposite to that of the groove on the other roll; and means for operating said rolls; substantially as set forth.

2. The combination of the roll 1, provided with the heads 5, and having longitudinal grooves 9, and a spiral groove 10; the roll 2, 25 provided with a head 6, and having similar longitudinal grooves 9, and a spiral groove 10; means of support for such rolls; and means of operation thereof; substantially as described.

3. In a device of the character described, 30 a pair of rolls each being provided with longitudinal grooves and spiral grooves forming spiral series of teeth, the teeth of each roll meshing with the teeth of the other roll and the direction of the spiral arrangement of teeth being the same on both rolls, and means for rotating the rolls in opposite directions.

In testimony whereof I affix my signature in presence of two witnesses.

EDWARD E. JONES.
